UNITED STATES PATENT OFFICE.

ANDREW A. KRAMER, OF KANSAS CITY, MISSOURI.

TANK CONSTRUCTION.

1,341,214.

Specification of Letters Patent. Patented May 25, 1920.

Application filed December 22, 1919. Serial No. 346,714.

To all whom it may concern:

Be it known that I, ANDREW A. KRAMER, a citizen of the United States, residing at Kansas City, in the county of Jackson and State of Missouri, have invented certain new and useful Improvements in Tank Construction; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to tank construction and particularly to portable tanks generally supported upon a vehicle body or frame.

The invention contemplates the provision of an inexpensive and rigid rack-supporting bracket adapted to be applied to bolsters which form parts of the end sheets or partition sheets of a tank; for example, such as is shown in the patent to Lee Hall, No. 1,316,949 of September 23, 1919, and the bracket is so arranged with respect to the remaining portions of the tank, bolster and end sheets that a symmetrical effect is provided.

In the drawings,

Figure I is a perspective view of a tank constructed in accordance with my invention.

Fig. II is a fragmentary view of a bracket applied to the end of the bolster, and

Fig. III is a modified form of bolster and bracket.

35 Referring now to the drawings by numerals of reference:

1 designates a tank having the end sheets 2 and 3 and the partition sheets 4 and 5. The end sheets are provided with integral, downwardly projecting bolsters 6 and 7, the lower edges of which are provided with laterally projecting flanges 8 to rest upon and be secured to longitudinal sills 9 by suitable fastening devices, as for example, the bolts 10.

45 When the brackets are separate parts from the bolsters, the ends of the bolsters are provided with vertical flanges 11 against which the vertical flanges 12 of the brackets 13 are adapted to abut, the flanges 12 preferably being co-extensive with the flanges 11, and said brackets 13 are provided with laterally projecting, horizontal flanges 14 to receive the can racks 15 which may be bolted thereto in a convenient manner. The flanges 12 and

55 13 are provided with alining openings to

receive the fastening devices or bolts 16 and 17, as clearly indicated in Fig. II, so that when the parts are in the position shown in Fig. III, the brackets will, in effect, be lateral extensions of the bolsters 6 or 7, as the case may be, and upon these may be secured the can racks, there being openings 18 and 19 in the flanges 14 to receive the fastening devices for securing the racks in place.

In Fig. III I have shown a slightly modified form of end sheet, bolster and rack in which the end sheet 20 is provided with an integral bolster 21 having a flange 22 to engage the side sill and an integral, laterally projecting bracket member 23 with a top lateral flange 24 to receive the can rack in substantially the same manner as the bracket shown in Figs. I and II.

When the parts are in place, a symmetrical, rigidly-carried bracket is supported by the bolster which not only serves a useful purpose but enhances the general appearance of the tank.

If desired, the bolts for the bracket 13 may be introduced into any of the openings 11' so that the bracket is vertically adjustable with respect to its bolster.

What I claim and desire to secure by Letters-Patent is:

1. A tank comprising a tubular body portion, sheets for closing the tubular body portion, tank supports in the plane of the sheets, and can rack brackets carried by the tank supports, the outer faces of the brackets being in the plane of the outer faces of the tank supports.

2. A tank support having end flanges projecting at right angles thereto, can rack brackets having vertical flanges abutting against the flanges on the tank support, means for securing the two flanges together, and means on the bracket for engagement by a can rack.

3. A tank support having a laterally projecting bracket member, the outer face of which is in the plane of the outer face of the tank support, said bracket having a laterally projecting flange upon which a can rack may rest, a sheet for engaging the tubular body portion of a tank, the sheet having an integral bolster for supporting the tank, and a laterally projecting can rack bracket carried thereby, said bracket having a flange horizontally disposed and said bracket having its outer face in the plane of the bolster,

4. A sheet for engaging the tubular body portion of a tank, the sheet having an integral bolster for supporting the tank, a laterally projecting sill-engaging flange on the 5 bolster, and a vertical, laterally projecting bracket-supporting flange on the end of the bolster.

5. A sheet for engaging the tubular body portion of a tank, the sheet having an integral bolster for supporting the tank, a laterally projecting sill-engaging flange on the 10 bolster, and a vertical, laterally projecting bracket-supporting flange on the end of the bolster, in combination with a bracket hav-

ing a horizontal flange and a vertical flange, 15 the vertical flange resting against and secured to the vertical flange of the bolster, the lateral flange of the bracket forming a can rack support.

6. A tank comprising a tubular body portion, sheets for closing the tubular body portion of the tank, supports in the plane of the sheets, and can rack brackets vertically adjustable on the tank supports, the outer 20 faces of the brackets being in the plane of the 25 outer faces of the tank supports.

In testimony whereof I affix my signature.
ANDREW A. KRAMER.
